UNITED STATES PATENT OFFICE.

GEORGE S. CARSON, OF IOWA CITY, IOWA.

ELECTRICAL CHOKE-COIL.

SPECIFICATION forming part of Letters Patent No. 769,057, dated August 30, 1904.

Application filed March 30, 1904. Serial No. 200,843. (No model.)

To all whom it may concern:

Be it known that I, GEORGE S. CARSON, of Iowa City, in the county of Johnson and State of Iowa, have invented certain new and useful 5 Improvements in Electrical Choke-Coils; and I do hereby declare the following to be a full, clear, and exact description of the invention, such as will enable others skilled in the art to which it appertains to make and use the same.

10 The object of this invention is to so arrange a choke-coil in reference to an electric line-wire and a lightning-arrester that the dynamo-current will follow the coil, while the static current will not, but will be forced to make 15 its escape along the lines of least resistance.

A further object is to so construct the choke-coil that it may form part of the line-wire and be wholly supported thereby.

The invention will be hereinafter fully set 20 forth, and particularly pointed out in the claims.

In the accompanying drawings, Figure 1 is a view in side elevation of my improved choke-coil. Fig. 2 is a central longitudinal sectional 25 view. Fig. 3 is a diagrammatic view showing the location of a coil and lightning-arrester relatively to a line-wire.

Referring to the drawings, 1 designates the choke-coil in its entirety; 2, the line-wire, 30 wherein the coil forms a part; 3, a lightning-arrester, (indicated only in outline in Fig. 3,) and 4 the ground-wire thereof.

The choke-coil consists of a tube 5, of porcelain or other non-conducting fireproof material, around which is closely wound coils of insulated wire 6, and a core 7, of soft iron, extended longitudinally through the tube and having at its ends yokes 8, wherein are mounted porcelain knobs 9, around which the ends 35 of the coil-wire are wound. The coil-wire is covered with the best rubber or gutta-percha insulation, so as to prevent the static current from jumping from one convolution to another. The conjunctive parts of the wire 40 coil—namely, the soft-iron rod and the porcelain knobs—constitute a positive direct connection for the line-wire and a support for the tube whereon the coil is wound. The choke-coil is secured direct to and made a

part of the line-wire, thus placing the choke 50 in circuit with the line-wire. The lightning-arrester is connected to the line-wire in juxtaposition to the choke-coil by a wire 10.

My improved choke-coil is constructed on the principle that the dynamo-currents will 55 follow the coil, while the static current will not, the latter being forced by the coil to make its escape along the line of least resistance, which is through wire 10 to the arrester and thence to the ground. The coil may be used 60 in connection with any well-known forms of lightning-arresters which are adapted to the voltage of the line upon which the coil and arrester are installed. The coil is adapted for out-of-door use on electric, telephone, tele- 65 graph, or other line wires upon which the lightning-current is damaging. It is intended to place the coils at frequent intervals on the line-wire, and thus prevent the lightning-current from extending the whole length of the 70 wire by diverting it to the arresters. The coils may be used without regard to the weather and can be placed indoors or outdoors, as the circumstances may require.

From what has been said it will be seen 75 that the choke-coils being fully insulated from the iron core the electric current will be forced through the coil and prevented from taking the shorter path across the direct connection established by the iron core and also 80 that the coil being attached in the body of the line becomes a part thereof, and in consequence lightning-currents of electricity will be readily diverted from the line-wires to the arresters, and thus prevented from following 85 the lines to their ends.

I claim as my invention—

1. In combination with an electric line-wire, and a lightning-arrester, a choke-coil located in juxtaposition to the connection between 90 the arrester and the wire, said choke-coil forming part of the said line-wire, and a direct connection between those portions of the line-wire at each end of the choke-coil.

2. In combination with an electric line-wire, 95 and a lightning-arrester, a choke-coil located in juxtaposition to the connection between the arrester and the wire, said choke-coil

forming part of the said line-wire, and comprising a coil of insulated wire and a support therefor around which such coil is wound, said support being itself supported by the 5 line-wire.

3. The herein-described choke-coil comprising a coil of insulated wire, a tube of insulating material around which such coil is wound, an iron core extended through said tube, and 10 blocks of insulation supported by said core at its ends and around which the ends of said coil are passed.

4. The herein-described choke-coil comprising a coil of insulated wire, a tube of insulating material around which such coil is wound, an iron core extended through said tube, and 15 having yoke-like ends, and blocks of insula-

tion supported by said ends and around which the ends of said coil are passed.

5. In combination, with an electric line-wire, 20 a coil of insulated wire secured at its ends to and forming part of said line-wire, a support of insulating material surrounded by said coil itself supported by said line-wire, and a lightning-arrester connected to said line-wire in 25 juxtaposition to said coil.

In testimony whereof I have signed this specification in the presence of two subscribing witnesses.

GEORGE S. CARSON.
